UNITED STATES PATENT OFFICE.

WALKER L. CROUCH, OF DAYTON, OHIO, ASSIGNOR TO OHMER FARE REGISTER COMPANY, OF DAYTON, OHIO, A CORPORATION OF NEW YORK.

LOCK FOR RECORDING-REGISTERS.

1,360,622.

Specification of Letters Patent.

Patented Nov. 30, 1920.

Application filed November 29, 1919. Serial No. 341,483.

To all whom it may concern:

Be it known that I, WALKER L. CROUCH, a citizen of the United States, residing at Dayton, in the county of Montgomery and State of Ohio, have invented certain new and useful Improvements in Locks for Recording-Registers, of which the following is a specification.

This invention relates to new and useful improvements in locks the object thereof being to provide a comparatively simple and inexpensive lock and at the same time an efficient one. The said lock is especially intended for locking the inclosing door of service recording machines. The lock, however, is of a character that renders it serviceable for general use and is therefore not restricted in its utility. A further object of the invention is to provide a lock which can not be picked.

The accompanying drawings afford ample illustration of the improved lock and reference is made thereto in general terms to be followed by a more particular or minute description. Of the said drawings, Figure 1 is a bottom plan view of a recording machine cabinet or casing, showing the improved lock applied thereto. Fig. 2 is a sectional view on the line —2—2— of Fig. 30 1. Fig. 3 is a sectional elevation on the line —3—3— of Fig. 5. Fig. 4 is a sectional elevation on the line —4—4 of Figs. 6 and 7. Fig. 5 is a section on line 5—5— of Fig. 3. Fig. 6 is a section on the line —6—6 of 35 Fig. 4. Fig. 7 is a section on line —7—7— of Fig. 4. Fig. 8 is a view of the key removed from the lock. Fig. 9 is a view of the tumbler removed from its position in the inner cylinder and Fig. 10 is a view of 40 the filler plate removed.

In a more particular description of the invention similar reference characters denote similar parts as shown in the drawings.

As shown in Figs. 1 and 2, —1— designates the casing of a type of recording machine adapted to record the service of an auto truck or like power driven vehicle. The door 2 of the cabinet or casing is hinged in the desired position and the lock is mounted in said door. The casing has an in-turned lip —3— at a suitable point to coöperate with the lock in securing the lid or door —2— in the closed position. This is one form of placing the lock in a serviceable 50 position. It will be readily seen the particular way in which the lock is mounted

depends upon the particular arrangement and form of door. The lock extends on the outside of the door and in addition to its service as a lock serves the further use of a 60 knob for the door. Referring to the particular construction of the lock, 4 designates an outer housing or cylinder which is made stationary by being attached to the door —2—. As shown in Fig. 3, an opening is 65 formed in the door and the surrounding edge enters a groove in the inner end of said outer cylinder. As shown in Fig. 2 the cylinder —4— extends on the outside of the door and is serviceable as a door knob. The 70 bore of the outer cylinder —4— at the inner end extends in an outward recess or notch —5—. Within the said outer stationary cylinder —4— a rotatable barrel or inner cylinder —6— is mounted, on the inner end of 75 which is fixed an eccentric locking plate —7— which is turned with said barrel to a position behind the up-turned lip —3— of the cabinet, to prevent the door —2— being opened, as shown in the broken line position 80 in Fig. 1. A half revolution of the key —8— moves the said locking plate —7— to this position and a further half revolution unlocks the door by moving said plate —7— out of that position. A locking plate or 85 tumbler —9— is mounted on a pivot pin —10— in the barrel. The upper edge of said tumbler has tapered surfaces —11— and —12— which are engaged by a lip —13— extending on one side of the inner 90 end of the key —8—. The said barrel —6— has a key slot —14— in which the tumbler —9— lies. When the key is inserted it lies at the side of said tumbler with the lip —13— of said key immediately above the 95 tumbler and in a position to engage the cam surface —11— of the tumbler. The width of the key slot —14— is reduced by a filler plate such as is shown in Fig. 10. The straight position —15— of this plate lies 100 below the path of the key and the inner end —16— thereof lies in the path of the key. The bar portion —17— in the outer end of said filler plate reduces the entrance width of the key slot. Thus the lock is effectively safe-guarded against picking or 105 being tampered with. A spring —18— is secured in the barrel —6— and exerts a force against the inner end of the tumbler —9— to move said end in the recess —5— 130 of the outer cylinder. This is possible when the barrel —6— is turned by the key until

the end of said tumbler is moved to said recess. When in this position the door —2— is locked and the key is withdrawn. The tapered surface —12— of the tumbler prevents the key being withdrawn while the barrel —6— is being rotated thereby. When the barrel —6— is moved to a position where the end of the tumbler —9— may be forced by the spring —18— into the recess —5—, and the key is moved out to clear the lip —13— from the tumbler to allow the surface —12— of said tumbler to move in the key may be withdrawn. The key can be withdrawn only when the door is locked by 10 the eccentric plate —7— being in the dotted position, Fig. 1.

Having described my invention, I claim:

1. A door lock comprising a stationary housing having a lateral recess extending from the inner end of the bore thereof, a rotatable cylinder in said housing having an opening in the side thereof adapted to register with the lateral recess in said housing, door-locking means carried by said cylinder, a cylinder-locking plate pivotally mounted in said cylinder and having an outward extended end which is adapted to enter the lateral recess in the housing when the opening in the side of the cylinder is caused to register with said recess and whereby said cylinder is prevented from being rotated, a filler plate within said cylinder reducing the width of the opening therein, a spring exerting normal outward pressure on the extended portion of said locking plate, and a key insertible in said locking cylinder and having a laterally extended lip adapted to engage the extended portion of said locking plate to remove it from the lateral recess in 30 the stationary housing whereby the locking cylinder is permitted to be rotated.
2. A door lock comprising a stationary housing having a lateral recess extending from the inner end of the bore thereof, a rotatable cylinder in said housing having an

opening in the inner side thereof adapted to register with the lateral recess in the housing, door-locking means carried on said cylinder, a cylinder-locking plate pivoted in said cylinder and having its inner end extended outwardly and provided with an outer tapered surface, a filler plate within the opening in said cylinder and having a bar on the outer end thereof which reduces the width of the opening in said cylinder through which the key is inserted, a spring engaging the extended end of said locking plate and exerting a normal outward pressure thereon, and a key having a lateral extension which is adapted to engage the tapered surface of the extended end of said locking plate to move the same out of the lateral recess in the housing whereby the locking cylinder may be rotated to unlock 60 said door.

3. A machine cabinet door lock adapted to be mounted on the cabinet door and consisting of a housing securable at its inner end to said door. Said housing having a longitudinal opening terminating on one side in a lateral recess, a rotatable barrel in said housing, an eccentric locking plate on the inner end of said barrel adapted to be moved therewith to a position to lock the door of the cabinet, a tumbler pivotally mounted in 70 said barrel having a tapered extended portion adapted to enter the recess in the housing when the barrel is moved to a position whereby the eccentric locking plate locks the cabinet door, said tumbler also having a rearward extended portion, and a key insertible in said barrel having a portion engaging the tapered extended portion of the tumbler, whereby said barrel is unlocked from the housing and may be rotated by the 75 key to unlock the cabinet door.

In testimony whereof I affix my signature.

WALKER L. CROUCH.
